BADGE OR SIMILAR ARTICLE

Elizabeth Will and Arthur E. Du Bois, Washington, D. C., assignors to the United States of America as represented by the Secretary of the Army

Application March 16, 1950, Serial No. 8,548

Term of patent 14 years

(Cl. D29—2)

To all whom it may concern:

Be it known that we, Elizabeth Will and Arthur E. Du Bois, citizens of the United States and residents of the city of Washington, District of Columbia, have invented a new, original, and ornamental Design for a Badge or Similar Article, of which the following is a specification, reference being had to the accompanying drawings, forming in a part thereof.

Fig. 1 is a front view of a badge or similar article, showing our new design.

Fig. 2 is a side view of the same.

The dominant features of our design reside in the portions shown in full lines.

It is understood that our design may be embodied in such articles as a medal, medallion, plaque, or sign, without departing from the spirit of our invention.

We claim:

The ornamental design for a badge or similar article, as shown and described.

ELIZABETH WILL.
ARTHUR E. DU BOIS.
